UNITED STATES PATENT OFFICE.

FREELAND W. OSTROM, OF BRIDGEPORT, CONNECTICUT, ASSIGNOR TO THE WHEELER & WILSON MANUFACTURING COMPANY, OF SAME PLACE.

BUTTONHOLE-SEWING MACHINE.

SPECIFICATION forming part of Letters Patent No. 623,618, dated April 25, 1899.

Application filed July 27, 1898. Serial No. 686,986. (No model.)

To all whom it may concern:

Be it known that I, FREELAND W. OSTROM, a citizen of the United States, residing at Bridgeport, in the county of Fairfield and State of Connecticut, have invented a certain new and useful Improvement in Cutter-Controllers for Buttonhole Sewing and Cutting Machines, of which the following is a full, clear, and exact description.

10 The object of my invention is to control positively the time of action of an automatically-actuated buttonhole-cutter, so as to insure the cutting of the buttonhole-slit in proper relation to the overseaming of the buttonhole no matter whether such buttonhole-slit is cut during the initial overseaming of the buttonhole or just prior to the completion of the overseaming.

15 The time of automatic actuation of the buttonhole-cutter, as herein shown and described, depends upon the step-by-step feed movement of the cloth-actuating mechanism, and such step-by-step feed movement is coincident with the formation of every alternate lock-stitch or coincident with the formation of every overseam-stitch—that is, the feed-pawl is caused to actuate the feed movement one step at one descent of the needle, and at its next subsequent descent the pawl is moved to 20 a position enabling it at the next or third descent of the needle again to advance a step in the step feed movement, the step-by-step feed movement occurring at the time the needle is out of the material and the descent of the 25 cutter being timed to occur just subsequently to the step-by-step feed movement and coincidentally with the descent of the needle for the formation of an edge stitch, and consequently in or nearly in line with the 30 needle relatively to the length of the button-hole.

35 The cloth-actuating mechanism, as herein shown and described, is adjusted first to overseam the left-hand side of the buttonhole, and 40 during the overseaming of that side of the buttonhole-slit the step-by-step movement occurs just prior to the formation of the edge stitch; but during the overseaming of the right-hand side the feed movement occurs 45 just prior to the formation of the depth-stitch.

50 So it will be understood that to cut the but-

tonhole-slit just prior to the finishing of the overseaming the cloth-actuating mechanism should be adjusted first to overseam the right-hand side of the buttonhole, such manner of 55 adjustment being fully described in my pending application, Serial No. 639,400.

The broad principle of my invention is embodied in a cutter the descent of which is insured to occur only when the cloth occupies 60 the proper relative position, the cutter-actuating mechanism performing the function of setting the cloth-actuating mechanism at a determinate position before it permits the cloth-actuating mechanism to actuate it. As 65 a form of mechanism for carrying out this invention I have provided the ratchet-wheel with a frictional control, which permits the ratchet-wheel and parts connected to and driven by it to be easily turned slightly backward, while their progressive movements are governed by a friction sufficient practically to control the overthrow caused by the momentum given these parts by the action of the driving-pawl, thus permitting as the pawl 70 returns for its subsequent feed actuation a slight backward movement of the cloth-actuating mechanism when resisted by the force necessary to connect the cutter-actuating mechanism with the depressor carried by the 75 needle-actuating mechanism.

For the purpose of this application I have illustrated and described the construction and operation of my invention in combination with so much of the buttonhole feeding and 80 sewing mechanisms illustrated and described in my pending application, Serial No. 639,400, and in connection with so much of the cutting mechanism shown and described in United States Patent No. 581,031, bearing 85 date April 20, 1897, as is necessary to show and describe an operative combination, to which application and patent reference will be hereinafter made.

In the accompanying drawings, illustrating 90 my invention, in the several figures of which like parts are similarly designated, Figure 1 is a view in perspective looking from the rear, showing an automatic buttonhole sewing and cutting machine constructed and arranged 95 as shown and described by the patent and pending application referred to. Fig. 2 is a 100

view in perspective of the friction-disk employed to control the movement of the cloth-clamp-actuating mechanism. Fig. 3 is a view in perspective of the ratchet-wheels and their driving-pawls, adjustable friction-spring, attached gear-wheels, feed connections, and pivotal stud, such parts being removed from the bed of the machine to show better their operative relation, the friction-disk illustrated in Fig. 2 being shown in dotted lines and in operative relation with the under side of the lower ratchet-wheel. Fig. 4 is a view in perspective of the lever for operatively connecting the cloth-actuating mechanism with the cutter-actuating mechanism. Fig. 5 is a perspective view of one of the friction-pieces. Fig. 6 is a perspective view of the coiled spring which coöperates with the lever of Fig. 4. Fig. 7 is a perspective view of the pivot-screw for said lever. Fig. 8 is a perspective view of the friction-spring of the ratchet-wheel. Fig. 9 is a perspective view of the upper end of the pivotal stud. Fig. 10 is a perspective view of a portion of the adjustable way in which the lever of Fig. 4 is pivoted, and Fig. 11 is a perspective view of said lever, way, and pivot-screw assembled.

Referring to Figs. 1 and 3, the ratchet-wheels D D', gear-pinion d, pawls b¹¹ d¹⁶, pawl-springs b¹⁵ d¹⁷, connecting-rods b⁸ d¹⁸, friction-spring b⁶, adjusting-nut b⁷, feed-rings b¹⁴ b¹⁴, connections b⁹ b⁹, the bed-plate A, the portion B of the under member of the cloth-clamp, the cross-slide b', stationary guideway b², and the adjustable guideway b³ for the cloth-clamp slide-frame b⁴, the connecting-link b¹³, the vibrating lever C, with its auxiliary lever c, the vibrating-lever stud c², the gear-wheel d', with its cam-groove d³, the spindle or stud b¹⁶, the slide-bar d⁴, the shouldered screw d⁵, the lever d¹⁰, the roller-screw x, the adjusting-stud d¹¹, the lever d¹², the screw d¹³, the link d¹⁴, the springs c⁶ c⁶, the screws c⁸ c⁸, and the adjusting-screws c¹⁰ c¹¹ are in construction and function similar to the parts correspondingly designated in my pending application, Serial No. 639,400, above referred to. From a comparison of Figs. 1 and 3 with my pending application referred to it will be readily understood that the gear-wheel d' derives its step-by-step rotary motion in the direction indicated by the arrow t through its connection with the pawl-actuated ratchet-wheel mounted on the spindle b¹⁶.

Referring to Fig. 1, the cutter-bar rock-shaft 1, its crank-arm 2, the cutter-bar collar 3, the cutter-bar 4, excepting as herein-after explained, and its attached cutter 5, the hooked collar or depressor 6, fast on the needle-bar rock-shaft 7, the collar 8, fast on the cutter-bar rock-shaft 1, the latch 9, pivoted at 10 to the collar 8, the spring 11, the stop-pin 12, the spring 13, the spring-collar 14, the collar 15, the stop-finger 16, the spring 17, the lever 18, the pivot-screw 19, the stop-pins 20 and 21, the flat spring 22, the collar

23, and its pin 24 are in their construction and operation the same as the corresponding parts shown and described in said Patent No. 70 581,031, but differently designated.

The stitch-forming mechanism, frame, and overhanging arm shown and described in this application are similar to corresponding parts employed in the pending application and United States patent herein referred to and comprise the well-known Wheeler & Wilson D¹⁰ sewing mechanism commonly used in connection with their well-known buttonhole-machines. 80

The manner of attaching the knife-clamp to the lower end of the cutter-bar, as shown and described in this application, differs somewhat from the manner shown and described in United States Patent No. 581,031 in that 85 an adjustable collar 25 is employed to adjust the clamp vertically with relation to the cutter-bar; but such change in construction comprises no part of my present invention.

The throat-plate 26 is of the construction 90 commonly employed in connection with the well-known Wheeler & Wilson automatic buttonhole sewing and cutting machine, and its details of construction are set forth in United States Patent No. 367,315, granted 95 July 26, 1887.

From the foregoing it will be understood that to connect operatively the cutting mechanism shown and described in United States Patent No. 581,031 with the cloth-actuating mechanism shown and described in my pending application, Serial No. 639,400, it is necessary to connect operatively the lever 18 with some part of the cloth-actuating mechanism, so that at the proper time in the over-seaming of the buttonhole the cutter will be automatically actuated to cut the buttonhole-slit. To accomplish this result, a lever 27, Figs. 1, 4, and 11, is attached to the adjustable way b³ by a pivot-screw 28, Figs. 1, 7, and 11, and held in the direction indicated by the arrow u, Figs. 1, 4, and 11, by a suitable coiled spring e, Figs. 6 and 10, located in the adjustable way b³ and encircling the screw 28, positioned to operate in the usual manner. The 100 lever 27 is constructed with two extending arms, one of which, 29, is positioned to coact with the lever 18, and the other, 42, Fig. 4, extends in the opposite direction, or nearly so, and under the edge of the gear-wheel d', so 105 that the roller-stud 30, rotating with the gear-wheel d', will strike the unexposed arm 42 of the lever 27, causing the arm or extension 29 to act upon the lever 18 and effect the automatic operation of the cutter in the same manner as if said lever 18 had been actuated by the movement of the cross-slide N of Patent No. 581,031. 110

Having sufficiently described the details of construction and operation of the cutting and 115 cloth-feeding mechanisms to show an operative combination, I will now proceed to describe in detail the construction and mode of operation of my present invention.

Prior to this invention it was common to mount the ratchet wheel or wheels upon a suitable pivotal stud, as is represented by b^{16} , said ratchet wheel or wheels resting upon a suitable flange or base, as is represented by 37 , and frictionally governed by a suitable washer of metal or other material on the upper side or by a suitable spring, as is represented by b^6 . In my present construction two friction devices are employed, the usual upper adjustable friction device and the added lower friction device 36 , Fig. 2.

Referring to Figs. 1 and 3, in the bed-plate A is secured a dog-pin 38 , partially in view in Fig. 1 and shown in Fig. 3 partly broken off, the friction-disk 36 being provided with a suitable opening 39 , diametrically somewhat larger than the dog-pin 38 , for the reception of said pin, permitting said disk when positioned, as shown by dotted lines, Fig. 3, to be slightly rotated on stud b^{16} , the friction-spring b^6 positioned to operate in the usual manner in connection with the upper side of the upper ratchet-wheel, with the exception that it is connected and mounted to partake of a like slight rotation. In order to enable the friction-spring b^6 to partake of this slight backward rotation, the hole f in the said friction-spring is made large enough to fit loosely upon the slabbed-off or squared portion g of the stud b^{16} , so that the said friction-spring will have the same movement as the under friction-disk 36 and will partake of the same lost motion as the said disk. This friction-disk 36 , in common with the parts with which it is connected, has at intervals a slight backward motion as a result of the recoil of the springs employed in connection with the cutter-actuating mechanism. To the friction-disk 36 are secured suitable friction-pieces 40 , preferably of rawhide, like friction-pieces 40^a , being secured to the arms 41 of the friction-spring b^6 .

From the foregoing it will be understood that in the operation of the machine the roller-stud 30 , carried by the cam-wheel d' , coacts with the unexposed arm 42 of the lever 27 (see Figs. 1 and 4) to move the arm 29 and the lever 18 in opposition to the springs 13 and 17 to effect a hitch-up between the clutch 9 and depressor 6 and that at such time the cloth and cutter-actuating mechanisms will, through the force exerted by said springs, move slightly backward as the pawl or pawls are moved backward for a subsequent actuation of the ratchet wheel or wheels, so that during such time as the cutting mechanism is under the domination of the cloth-actuating mechanism the feed movement is slightly reversed prior to every progressive movement for the purpose of avoiding an operative hitch-up between the latch 9 and depressor 6 excepting coincidently with the step-by-step feed movement.

The flange 37 of the pivotal stud b^{16} is of small diameter, and its frictional coöperation with a like amount of the under surface of the friction-disk 36 offers but a slight resist-

ance to the movement of the parts mounted on said pivotal stud and resting upon said flange and facilitates the partial rotation of such parts and parts actuated by them when resisted by the power which forces the cutter into action.

The friction device 36 (see Fig. 2) is cut away to accommodate the cam-wheel d' . (See Fig. 1.)

What I claim is—

1. In a buttonhole sewing and cutting machine, in combination, the feed-actuating mechanism, the cutter-actuating mechanism, and means, including upper and lower friction devices applied to the feed-actuating mechanism, whereby the engagement of said two mechanisms sets the same in a determined relative position preparatory to the actuation of the cutter, substantially as described.

2. In a buttonhole sewing and cutting machine, in combination the needle, needle-actuating mechanism, the feed-actuating mechanism, the cutter-actuating mechanism, and means including friction devices whereby the resistance of the cutter-actuating mechanism sets the feed-actuating mechanism in a determined position and means whereby the feed-actuating mechanism then actuates the cutter-actuating mechanism, substantially as described.

3. In a buttonhole sewing and cutting machine, in combination with the cutter-actuating mechanism, a cloth-actuating mechanism containing a plurality of friction devices constructed and arranged to permit a slight reverse movement of the cloth-actuating and cutter-actuating mechanisms, at such time as the feed movement of the cloth-actuating mechanism is resisted by the power necessary to force the cutter into action, substantially as described.

4. In a buttonhole sewing and cutting machine, in combination with the cutter-actuating mechanism, a cloth-actuating mechanism containing a plurality of friction devices arranged in operative relation to the opposite sides of the feed or ratchet wheel or wheels, said friction devices mounted to be easily turned slightly backward at such time as the feed movement of the cloth-actuating mechanism is resisted by the power necessary to force the cutter into action, substantially as described.

5. In a buttonhole sewing and cutting machine, in combination with the cutter-actuating mechanism, a cloth-actuating mechanism containing one or more rotating feed or ratchet wheel or wheels, mounted on a suitable pivotal stud and frictionally controlled on opposite sides by independently-mounted friction devices; said friction devices constructed and arranged to permit the cloth-actuating and cutter-actuating mechanisms to be easily turned slightly backward when resisted by the power necessary to force the cutter into action, substantially as described.

6. In a buttonhole sewing and cutting machine, in combination with stitch-forming mechanism the cutter-actuating mechanism, a cloth-actuating mechanism containing one or more rotating feed or ratchet wheel or wheels, mounted on a suitable pivotal stud secured in the machine-bed, and frictionally controlled on opposite sides by independently mounted friction devices, and a suitable stop to predetermine the extent of the reverse

movement of the cloth-actuating mechanism when resisted by the power necessary to force the cutter into action, substantially as described.

In testimony whereof I have hereunto set my hand this 25th day of July, A. D. 1898.

FREELAND W. OSTROM.
